LAMP BASE

John Roberts, Honolulu, Territory of Hawaii

Application July 1, 1952, Serial No. 20,428

Term of patent 14 years

(Cl. D48—20)

To all whom it may concern:

Be it known, that I, John Roberts, citizen of the United States, residing at Honolulu, in the Territory of Hawaii, have invented a new, original, and ornamental Design for a Lamp Base, of which the following is a specification; reference being had to the accompanying drawing forming part thereof.

In the drawing:

Figure 1 is a front elevational view of a lamp base showing my new design;

Figure 2 is a side elevation;

Figure 3 is a rear elevation;

Figure 4 is a cross-section taken along the line 4—4 of Figure 1.

The dominant features of my design are shown in solid lines in the drawing.

I claim:

The ornamental design for a lamp base, a shown and described.

JOHN ROBERTS.
